VIBRATION DAMPENING SUPPORT FOR
MACHINES

Frederick F. Zeier, Stratford, Conn., assignor to
The Singer Manufacturing Company, Elizabeth, N. J., a corporation of New Jersey

Application July 17, 1948, Serial No. 39,267

1 Claim. (Cl. 248—22)

1

This invention relates to supports for machines and it has as an object to provide an improved support which will dampen the vibrations set up by the machine and thereby deaden the noise normally produced by such vibrations.

A high speed sewing machine, and especially a so-called feed-off-the-arm sewing machine which is mounted in "outboard" fashion, is a good example of a machine which sets off substantial vibrations and produces considerable noise during its operation. This invention will, for convenience, be shown and described in connection with that type of machine but it is to be understood that the invention is equally adaptable to other types of machines.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the drawings, Fig. 1 is a front elevation of a feed-off-the-arm sewing machine and a supporting table therefor, embodying the present invention.

Fig. 2 is an end elevation of the machine and table shown in Fig. 1.

Fig. 3 is a plan view of the machine and the top of the table shown in Figs. 1 and 2.

Fig. 4 is an enlarged plan view of a portion of the table with two of the improved vibration dampening supports secured therein.

Fig. 5 is a vertical section on the line 5—5 of Fig. 4.

Fig. 6 is a vertical section on the line 6—6 of Fig. 4.

Fig. 7 is a vertical section on the line 7—7 of Fig. 4.

Referring more specifically to the drawings, the invention is disclosed as embodied in a sewing machine table comprising a frame including vertically disposed and vertically adjustable legs 1, horizontal cross-braces 2 and a horizontally disposed table-top T secured upon the upper ends of said legs. The frame carries a machine-driving electric transmitter M, having a pulley P which drives a machine operating belt B; a transmitter-controlling treadle C having operative connections, designated generally as c, with the transmitter; and a presser-foot lifting treadle L connected, by means designated generally as m, with the presser-foot lifter of a sewing machine hereinafter referred to.

2

A sewing machine S, shown herein as a feed-off-the-arm machine, is mounted upon the table-top T through the medium of my improved vibration dampening and sound deadening supports now to be described.

The table-top T is formed with a circular opening 3 and an elongated opening 4. At opposite sides of the opening 3 the table-top is formed with substantially semicircular cavities 5 which extend approximately half way through the table-top and afford spaced supporting ledges 6. Extending across the opening 3 and having its opposite ends resting upon the ledges 6 in the cavities 5, and secured by suitable bolts is a strip 15 of vibration dampening material 8 preferably, but not necessarily, formed of a fibrous material impregnated with a suitable binder. A material which has been found ideal for this purpose consists of layers of canvas impregnated with rubber and pressed into a relatively solid mass. The end portions of the strip 8 are formed with cavities 9 which receive the large heads 10 of clamp bolts 11, the shanks of which extend through the strip 8 and through apertures 12 in the ledges 6. Washers 13 and nuts 14 on the threaded lower ends of the bolts draw the strip 8 into clamping contact with the ledges 6 and maintain the ends of the strip in the cavities with the upper surface of the strip projecting above the upper surface of the table-top T, as shown in Fig. 5.

At the opposite ends of the elongated opening 4, the table-top likewise is formed with cavities 15 and underlying ledges 16 upon which rest the end portions of a strip 17 of vibration dampening and sound deadening material similar to that of which the strip 8 is made. The strip 17 is provided with cavities 9' for the reception of the heads 10' of bolts 11', carrying washers 12' and nuts 13', by means of which the strip 17 is clamped upon the ledges 16 with the upper surface of the strip above the upper surface of the table-top in the same manner as the strip 8 is clamped upon the ledges 6.

45 The base x of the machine S, has a three-point support on the strips 8 and 17, as will now be described. As shown most clearly in Figs. 3, 4 and 5, the right rear corner of the base has a foot or pad b¹ which bears upon the strip 8 between the opposite walls of the opening 3. This foot is secured to the strip 8 by a bolt 18 and nut 19 (see Fig. 5). At its forward edge, the base x has a two-point contact with the strip 17. As seen in Fig. 7, the right hand edge of the base x is provided with a foot or pad b² which rests upon the member 17 adjacent one end of

the elongated opening 14 and is secured to the member 17 by a bolt 20 and nut 21. Near its opposite edge, the base has a depending boss 22 which seats upon the member 17, adjacent the opposite end of the opening 4, and is held in contact with that member by a bolt 23.

It is to be noted that the feet b^1 , b^2 and the boss 22 each bears against its associated vibration dampening member inwardly of and adjacent to one end of the opening 3, 4. Thus the weight of the base and the machine carried thereby is transmitted to the vibration dampening supports in shear relation with the walls of the openings and not merely through compression of the vibration dampening material.

From the foregoing, it will be apparent that this invention has provided a novel vibration dampening and sound deadening means for machines, which is effective, relatively inexpensive, and which may be readily embodied in the frame upon which the machine is supported.

Having thus set forth the nature of the invention, what I claim herein is:

A vibration-dampening support for a machine, comprising, a horizontal table-top having a vertical opening extending therethrough and a pair of cavities having vertical side walls and a horizontal bottom wall and being disposed within the upper surface of said table-top and communicating with said opening at opposite sides thereof, an elongated resilient vibration-dampening member having a width less than that of said opening and being disposed across said opening with each of the two opposite end portions of said

member being snugly received within a respective one of said cavities, a pair of bolts each including a threaded shank and an enlarged head, each of said bolt shanks passing through a respective one of the opposite end portions of said member and the base-portion of a respective one of said cavities, a nut mounted upon the distal end of each of said bolt-shanks, each of said bolts with its associated head and nut being effective forcibly to compress a respective one of the opposite end portions of said member into its associated cavity and against the bottom wall of such cavity so that the opposite end portions of said member will have their marginal side wall portions supported by the corresponding side wall portions of the cavities, and a stud passing through an intermediate portion of said member at a location over said opening for supporting a machine upon said member.
